PLATE SPRING

Theodore R. Weber, Latrobe, Pa., assignor to
American Locomotive Company, New York,
N. Y., a corporation of New York

Application May 16, 1939, Serial No. 273,873

4 Claims. (Cl. 267—54)

This invention relates to plate springs and more particularly to spring end clips therefor.

The object of the invention is to provide a replaceable self-retaining spring end clip, having a bearing face for supporting a spring hanger, which may be assembled with the spring, or disassembled, at any time by a longitudinal sliding movement over the end of the spring main plate, and is held in place on the spring against accidental removal by means which do not prevent its removal when desired.

Other and further objects of and advantages achieved by the present invention will be apparent from the following description of an approved embodiment thereof and the claims appended hereto.

Referring to the drawing forming a part of this application, Figure 1 is a side elevation of a semi-elliptic spring embodying the present invention; Fig. 2 is a plan view of the spring, the spring end clip at the right hand side of the spring being removed; Fig. 3 is an enlarged side elevation of the spring end clip; Fig. 4 is an end view of the clip, the adjacent plates being indicated in dot and dash lines; Fig. 5 is an inverted plan view of the clip; and Fig. 6 is a side elevation, similar to Fig. 1, of a portion of the spring showing the method of assembling the clip with the spring and removing it therefrom.

The spring of the present invention, indicated by the reference numeral 1, is in the main a conventional semi-elliptic spring consisting of a plurality of plates secured together by a spring band 2. In accordance with the present invention, the main plate 3 has a portion cut away at each side of each of its end portions providing a tongue 4 of a reduced width at each end of the plate. The sides 5 of the tongue are shown parallel to each other and to the sides of the spring and are connected to the sides of the body portion 6 of the main plate by rounded edges 7. It will be understood, however, that the sides 5 need not be parallel but may, for instance, converge outwardly toward the adjacent end of the spring if desired. The reduced tongue extends to the end of the spring adjacent thereto.

The second or inner plate 8 of the spring is also modified in accordance with the present invention. It has a portion 9 disposed under and adjacent each tongue 4, each portion 9 being of a width less than the width of the adjacent tongue. The portions 9 are shorter than the tongues 4 and are spaced each from the adjacent end of the spring, thereby leaving end portions 10 between each portion 9 and the adjacent end of the

spring. The sides 11 of each portion 9 are shown parallel to each other and to the sides 5 but they may be of any desired shape. The sides 11 of each portion 9 are connected to the sides of the body portion 12 of the inner plate and to the sides 5 of the end portion 10 adjacent thereto by rounded edges 13.

The end portions 10 are shown of the same width as the body portion 12, but it is only necessary for the purpose for which they are employed, that they be wider than the portion 9. These end portions hold the spring end clip, which is carried on the tongue 4, as will later be more fully described, from moving outward away from the spring. However, if other means are provided for this purpose, the end portions may be eliminated and the portion 9 may extend to the end of the spring similarly to the tongue 4. Such other means might be, for instance, a flange turned up from the end edge of the inner plate 8 sufficiently so that when the ends of the main and inner plates are in engagement, the flange would overlap the outer edge of the clip.

Each tongue 4 and adjacent portion 9 form a portion 14 T-shape in cross section. If desired, the portion 9 need not be provided on the second plate of the spring but may be, for instance, on the third or fourth plate. In such a case, the plates intervening would be shaped similar to the main plate so that a T shape portion would still be present. The T-shape is shown as formed of straight lines at right angles to each other, but it will be understood that the shape need only be substantially T-shape in cross section and that, for instance, a V-shape could be employed. The term T-shape is therefore employed in the specification and claims in its broad sense and is employed to designate the tongue and groove connection permitting longitudinal sliding between the spring end clip and the end portion of the spring, as will later be described.

The spring end clip 15 consists of the usual body portion 16 having a hanger bearing outer face 17 and an inner spring-engaging face 18. An angular flange 19 projects from the inner face 18 at each longitudinal side of the clip, having a vertical leg 20 perpendicular to the inner face 18 and a horizontal leg 21 parallel to the face 18. The legs 21 are directed toward each other and with the legs 20 and the portion of the face 18 adjacent thereto form grooves for a purpose that will presently appear. The flanges 19 are disposed centrally of the clip and are of a length substantially that of the portion 9 and the space between the legs 21 is at least equal to the width of the portion 56.

9 to permit proper interfitting of the parts. The corner formed by the junction of the leg 20 with the face 18 is rounded out forming a fracture-resisting groove 22. The corners of the legs 20 and 21 are also rounded off as shown in Fig. 5.

The flanges 19 thus form, with the inner face 18, a T-shape groove 23 running longitudinally of the clip and this groove, when associated with the T-shape portion 14, serves to hold the clip upon the spring against vertical displacement movement, as will later more fully appear.

The advantages of the present invention will be better understood from a brief description of the method of assembling the clip with the spring, and removing it therefrom. To assemble the clip of the spring, as shown in the drawing, a wedge *a* or similar tool is forced between the main plate and inner plate 8, separating the plates as shown in Fig. 6. The clip is introduced to the main plate so that the tongue 4 will slide into the grooves formed by the legs 20, 21 and the inner face 18. The clip is moved along the tongue toward the band 2 until the flanges 19 are directly above the respective cut-out portions providing the portion 9. The wedge is then withdrawn, and the main plate end portion thereupon springs back upon the inner plate. The flanges 19 will then be disposed one on each side of the portion 9, with their outer transverse sides opposed to the adjacent sides of the end portion 10, the end portion 10 being wide enough to provide parts overlapping the flanges 19. The clips will thus be held against vertical displacement movement by the legs 21, from outward longitudinal displacement movement by the end portions 10 and from inward longitudinal displacement movement by the ends of the body portions 6 and 12 of the main and inner plates which are adjacent the inner transverse sides of the flanges 19.

If it is necessary to remove the clip for any reason, such as to replace it, the main and inner plates are separated by the wedge *a* once more and the clip slid off in an obvious manner.

When the portion 9 is formed on a plate inward of the plate 8, as has already been mentioned, the wedge will be inserted between the plate containing the portion 9 and the adjacent plate outwardly therefrom, the assemblage and removal of the clip being effected in a manner similar to that already described.

As the main plate does not serve to retain the clip from sliding off the spring, fracture of this main plate will not result in loss of the clip by such sliding off.

While there has been hereinbefore described an approved embodiment of this invention, it will be understood that many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. A plate spring comprising a plurality of plates secured together by a spring band; and a spring hanger clip carried by said spring and seated on the main plate at an end thereof, said clip having a longitudinal T-shape groove and said spring having a portion, T-shape in cross section, disposed in said groove whereby said clip is secured to said spring.

2. A plate spring comprising a main plate and an inner plate secured together by a spring band; and a spring hanger clip carried by said spring and seated on said main plate at an end thereof, said clip having a longitudinal T-shape groove and said spring having a portion, T-shape in cross section, disposed in said groove whereby said clip is secured to said spring against vertical displacement movement relative thereto, said inner plate having means cooperating with said clip securing said clip to said spring against longitudinal displacement movement relative thereto.

3. A plate spring comprising an outer plate having end portions reduced in width from the outer ends of said plate inward to a predetermined extent to form a tongue at each end of said plate, and an inner plate having portions reduced in width from the width of said tongues and disposed one adjacent each of said tongues, each providing, with said tongue adjacent thereto, a portion T-shape in cross section, said inner plate having spring hanger clip-retaining parts; and a spring hanger clip disposed over each of said T-shape portions and seated on said outer plate, said clips each having a T-shape longitudinal groove cooperating with said T-shape portion adjacent thereto, whereby said clips are held against vertical displacement movement relative to said spring, said retaining parts coacting with said clips and holding said clips against longitudinal displacement movement relative to said spring.

4. A plate spring comprising an outer plate having end portions reduced in width from the outer ends of said plate inward to a predetermined extent to form a tongue at each end of said plate, and an inner plate having portions reduced in width from the width of said tongues and disposed one adjacent each of said tongues, each providing, with said tongue adjacent thereto, a portion T-shape in cross section, said inner plate reduced portions each being spaced from the adjacent end of said inner plate to provide end portions for said inner plate of a width greater than the width of said inner plate reduced portions; and a spring hanger clip disposed over each of said T-shape portions and seated on said outer plate, said clips each having a T-shape longitudinal groove cooperating with said T-shape portion adjacent thereto, whereby said clips are held against vertical displacement movement relative to said spring, said end portions coacting with said clips and holding said clips against longitudinal movement thereto-ward relative to said spring.
